UNITED STATES PATENT OFFICE

2,493,048

CARTRIDGE CLIP LOADING DEVICE

Ervin F. Wangrow, Bingham, Ill.

Application October 30, 1944, Serial No. 561,146

5 Claims. (Cl. 86—47)

(Granted under the act of March 3, 1883, as amended April 30, 1928; 370-O.G.757)

1.

The invention described herein may be manufactured and used by or for the Government for governmental purposes without the payment to me of any royalty thereon.

My invention relates to cartridge clip loading devices and its general object is to provide a device of this character in which cartridges may be aligned in a single row and in which a pre-determined number of cartridges may be inserted in a clip by a single movement, thus avoiding the delay and loss of manpower involved in loading the clips by hand.

A further object of my invention is to provide a device of this character which is economical to manufacture, which has few parts, which is positive in operation, and which is light of weight and occupies but very small space, and therefore may be readily transported from place to place.

With these and other objects in view as will hereinafter more fully appear, and which will be more particularly pointed out in the appended claims, reference is now made to the accompanying drawings forming a part of this application, in which:

Figure 1 is a top plan view of my improved cartridge loading device, illustrating the pivoted arms in extended position with the cartridges to be aligned positioned therebetween;

Figure 2 is a view similar to the view of Fig. 1, illustrating the pivoted arms in parallel relation with the cartridges aligned in a single row, with the loading fork in loading position;

Figure 3 is a side elevational view, partly broken away, with the loading fork in loading position;

Figure 4 is a transverse, sectional detail view, on an enlarged scale, illustrating the position of the loading fork on the pivoted arm, taken on the line 4—4 of Fig. 2;

Figure 5 is a perspective view, on an enlarged scale, of the loading fork; and

Figure 6 is a horizontal, sectional view, on an enlarged scale, taken on the line 6—6 of Fig. 3, looking in the direction of the arrows.

Referring now to the drawings in which similar reference characters represent similar parts, my invention comprises a base 2 of wood, plastic, or any other suitable composition or metal, provided with identical supporting members 4 which are secured to the base by means of conventional identical bolts or screws 6. A transverse member 8 is affixed by means of conventional bolts or the like 10 across one end of the base. Base 2 is also provided with a slotted recess 12 adapted to receive a cartridge clip 14 the base of clip 14 abutting transverse member 8 which acts as a

support and stop for said clip. Arms 16 and 18 are pivotally connected to base 2 by means of identical bolts or the like 20, whereby when the arms are brought to a parallel position, they will form a channel in a prolongation of slot 12, the channel being wide enough to snugly hold a single row of cartridges 21 of the caliber for which the device is constructed, in upright position with the ball ends up. The loading fork, which will be described below, is then placed in position behind the number of cartridges desired to be inserted in the clip, and manually pushed toward the clip, thereby inserting the cartridges into the clip. It will be noted that arm 18 is provided with graduations 22, which may be numbered if desired, to facilitate the placing of the loading fork at the proper point, behind the exact number of cartridges desired to be inserted.

The loading fork comprises a handle 24, with an inverted channel-shaped member 26, and an angular finger 28 secured to the base thereof by means of a conventional bolt 30 extending longitudinally through the handle. The inverted channel member 26 is adapted to fit over the arms 16 and 18 when the arms are parallel, while finger 28 extends down between the bars and impels the cartridges along the channel and into the clip 14, when manual force is applied to the handle 24.

The free end of arm 18 is provided with a slotted recess 32 adapted to receive one end of latch 34 which is pivotally connected to the arm 18 by means of a conventional bolt 36. Latch 34 is provided with an arm 38 and with shoulders 40 and 42, shoulder 40 being adapted to engage the inside surface of arm 18, while shoulder 42 engages the outside surface of arm 16 when the arms are in parallel relation, thereby maintaining the arms in loading position. Arm 18 is provided with an annular recess in its inner surface, adapted to receive one end of coil spring 44, the other end of said spring engaging arm 38 of latch 34, whereby the latch 34 is normally maintained at an angle of 90° from the arm 18 with the shoulder 40 engaging the inner surface of arm 18 as shown in Fig. 6. The free end of arm 16 is provided with a transverse recess 46 adapted to receive latch 34, as shown in Fig. 6. The inner end of the recess may be provided with an angularly disposed metallic guide and reinforcing member 48, maintained in position by conventional identical bolts or screws 48. When the arms are brought to the parallel position, shoulder 42 engages the inclined surface of guide 46, spring 44 is contracted, storing force therein, until shoulder 42 clears the slot in arm 16, when the latch

is locked in position by the action of spring 44 and is maintained in this position until manually released.

In operation, the free ends of arms 16 and 18 are spread to the position shown in Fig. 1, and a box of cartridges, usually 50 in number, are placed therebetween on the base with the ball ends up. The arms are manually pressed together, with a slow semicircular motion, care being exercised not to apply excessive pressure, until all the cartridges are brought into alignment in a single row, as illustrated in Fig. 2, when the latch 34 locks the arms together. The loading fork is then placed over the arms 16-18 with the finger 28 behind the number of cartridges to be loaded. Manual pressure is then exerted on arm 24 of the fork and the cartridges are forced into the clip.

While I have illustrated and described the invention in some detail, it is to be understood the invention is not to be limited to such detail, but only by the spirit of the invention and the scope of the appended claims.

I claim:

1. A cartridge clip loading device of the character described, comprising a base, means for holding a cartridge clip in said base, a movable arm pivotally connected to said base, cartridge engaging means on said base adjacent said arm, said arm being adapted to be moved relative to said engaging means whereby cartridges placed between said engaging means and said movable arm may be aligned against said engaging means in a single row adjacent said clip, and means cooperating with said movable arm for inserting the aligned cartridges into the clip.

2. A cartridge clip loading device of the character described, comprising a base, means for holding a cartridge clip in said base, a pair of arms pivoted at one of their ends to said base and adapted to receive therebetween a plurality of cartridges, means on said arms for holding the same towards each other whereby the cartridges are aligned in a single row between said arms, and means for inserting said cartridges into the clip.

3. A cartridge clip loading device of the character described, comprising a base, means for holding a cartridge clip in said base, a pair of arms pivoted at one of their ends to said base and adapted to receive a plurality of cartridges between said arms, means for locking said arms in parallel relation whereby the cartridges are held in alignment for insertion into the clip, and means for inserting the aligned cartridges into the clip.

4. A cartridge clip loading device of the character described, comprising a base, a recess in said base for holding a cartridge clip, a pair of arms pivotally connected to said base whereby a plurality of cartridges may be brought into a single row in alignment with said clip, and manually operable means associated with said base for inserting a selected number of the cartridges into the clip.

5. A cartridge clip loading device comprising a base horizontally disposed and so dimensioned so as to be capable of receiving directly the entire contents of a box containing rows of cartridges with said cartridges standing upright, means for holding a cartridge clip in said base, means on said base for moving the cartridges into a single row in alignment with said clip with the plurality of cartridges in upright position, and means for progressively inserting the aligned cartridges into the clip.

ERVIN F. WANGROW.
